COUPLER CENTERING DEVICE

Original Filed Feb. 18, 1929

UNITED STATES PATENT OFFICE

2,066,009

COUPLER CENTERING DEVICE

Elmyr A. Laughlin, deceased, late of Oregon, Ill.,
by Bessie D. Laughlin Spoor, administratrix,
Oregon, Ill., assignor to Consolidated Metal
Products Co., Chicago, Ill., a corporation of
Delaware

Refiled for abandoned application Serial No.
340,850, February 18, 1929. This application
February 26, 1936, Serial No. 65,849

6 Claims. (Cl. 213—21)

The invention relates to improvements in coupler centering devices for use on railway cars and has for its primary object the provision of an improved construction of this character capable of economical construction and highly efficient in use, the present invention being an improvement on the construction disclosed in a prior Patent No. 1,586,252, granted on May 25, 1926, for Coupler centering devices, and constituting the subject matter of abandoned application, Serial No. 340,850, filed February 18, 1929.

Another object of the invention is the provision of an improved construction of this character so constructed and arranged as to prevent disrupting of the same from any cause during use.

Other objects will appear hereinafter.

The invention consists in the combinations and arrangements of parts hereinafter described and claimed.

The invention will be best understood by reference to the accompanying drawing forming a part hereof and in which

Fig. 1 is a vertical transverse section taken through the lower portion of a coupler stem support of a railway car and showing a coupler centering device embodying the invention in position of use;

Fig. 2, a similar view of the centering device detached and showing the parts in position for disengagement or re-engagement; and

Fig. 3, a section taken substantially on line 3—3 of Fig. 1.

The preferred form of construction, as illustrated in the drawing, comprises a base 5 in the form of a flat bearing plate having a central up-standing post 6 provided at its top with a T-head 7. Arranged on the base 5, on opposite sides of the post 6, are two rocker members 8 having teeth 9 on their upper and lower bearing surfaces, said rockers being eccentric in form so as to exert a lifting or elevating action when rocked either away from the center, said rockers being in all substantial and material respects the same as the corresponding rockers disclosed in my said prior patent. The upper and lower bearing surfaces 10 of said rockers 8 are each provided at their centers with a flat spot 11, said flat spot having a tendency to maintain the parts in central positions and causing quick elevating action as the rockers depart from central position in either direction, as will be readily understood. The base 5 is provided with recesses 12 in the form of openings extending entirely through said base to receive and accommodate the teeth 9 on the lower bearing surfaces of the

rockers 8, thereby maintaining said rockers in proper cooperative relationship with said base during normal operations thereof.

A coupler carrying member 13 is supported upon the rockers 8, said carrying member 13 being provided with a recess or pocket 14 adapted and arranged to receive the coupler stem 15 and serve as a support therefor. A central shallow grease recess 16 is also provided in the upper surface of the carrying member 13 for purposes of lubrication between said carrying member and said coupler stem. The carrying member 13 is provided with recesses or pockets 17 to receive and accommodate the teeth 9 on the upper bearing surfaces of the rockers 8, thereby holding the carrying member in proper cooperative relationship with said rockers during operation.

The carrying member 13 is provided at its central portion with two depending flanges 18 embracing the upper portion of the post 6, and a T-slot 19 is provided in the under side of the carrying member 13 to receive the T-head 7 on the post 6. As best shown in Fig. 2, the upper surfaces 20 of the retaining ledges of the T-slot 19 slope downwardly both ways from the center, thereby permitting elevation of the carrying member 13 due to the eccentricity of the rockers 8 as they rock either way from central position. Openings 21 are also provided at each end of the slot 19, thereby providing for engagement with and disengagement from the T-head 17, as indicated in Fig. 2, when the carrying member 13 is rocked to extreme lateral position in either direction. By this arrangement, the mounting for the coupler carrying member 13 may be readily assembled or taken apart when removed from its normal support but cannot become disrupted during use as long as the extreme lateral movement indicated in Fig. 2 is prevented.

In actual use upon a railway car, the parts of the device above described are inserted in a channel or pocket 22 provided in a cross-piece 23 of an ordinary coupler supporting member 24, said supporting member 24 having a central opening for the passage and lateral swinging of the coupler stem 15, as indicated in Fig. 1. The length of the channel 22 is such that upon lateral movement of the carrying member 13 in either direction, the ends thereof strike the ends of the channel before the extreme lateral movement indicated in Fig. 2 has been reached, so that, in normal use of the device, it is impossible to disengage or disrupt the parts as long as the coupler supporting member 24 remains intact. Obviously, however, the assembled parts of the device

may be readily removed from the channel or pocket 22 whenever the coupler stem 15 has been removed.

In order to insure proper positioning of the device in the pocket 22, the ends thereof are provided with positioning lugs 25 having upper inclined cam surfaces 26 and thereby providing a space centrally in the bottom of the pocket 22 which will just accommodate the base 5 and thus insure proper positioning of the parts in said pocket. Dirt escape openings or slots 27 are also provided in the bottom 23 of the coupler support 24 to register with the openings 12 and thereby permit of ready escape of dirt, cinders, or the like from the pocket 22.

It is to be noted that, owing to the eccentricity in shape of the rockers 8 when the coupler stem 15 swings to either side of its normal central position during uncoupling operations, the said stem will be slightly elevated so that its weight and the weight of the associated parts will automatically return said coupler stem to central position upon release by the uncoupling action. In this way, the coupler head on the coupler stem will always be automatically maintained in central coupling position.

It is also to be noted that the carrying member is provided with lateral flanges, best shown in Fig. 3, which rest over and immediately adjacent the top edges of the pocket 22 so that, when the parts become slightly worn, these flanges rest upon said edges in central position but lift therefrom during lateral movement. This relieves the rockers of wear to some extent.

The construction disclosed provides a simple and efficient automatic coupler centering device which is capable of economical manufacture, may be readily assembled or taken apart as the exigencies of actual service may require, and which cannot become disrupted or disorganized in actual service. The specific form and arrangement of parts constitutes a simple and effective one for the purpose.

While I have illustrated and described the preferred form of construction for carrying the invention into effect, this is capable of modification and variation without departing from the spirit of the invention. I therefore do not wish the patent to be limited to the precise details disclosed but to include also such variations and modifications as fall within the scope of the appended claims.

I claim:

1. A device of the class described comprising a base; a central headed post on said base; rocker members on said base on opposite sides of said post; and a coupler stem carrying member supported on said rockers, there being a T-slot in the under side of said carrying member to receive the head of said post, adapted and arranged to prevent disengagement of said carrying member during normal operations of said rockers but permitting disengagement and re-engagement upon extreme lateral movement of said carrying member.

2. A device of the class described comprising a base; a central T-headed post on said base; rocker members on said base on opposite sides of said post; a coupler stem carrying member supported on said rockers, there being a T-slot in the under side of said carrying member to receive the head of said post, adapted and arranged to prevent disengagement of said carrying member during normal operations of said rockers but

permitting disengagement and re-engagement upon extreme lateral movement of said carrying member; and a support for said base adapted and arranged to prevent such disengaging lateral movement of said carrying member when the device is in operative position thereon.

3. A device of the class described, comprising a base; a central T-headed post on said base; eccentric rocker members on said base on opposite sides of said post; a coupler stem carrying member supported on said rockers, there being a T-slot in the under side of said carrying member to receive the head of said post, the retaining ledges of said slot sloping downwardly both ways from the center, adapted and arranged to prevent disengagement of said carrying member during normal operations of said carrying member but permitting disengagement and re-engagement upon extreme lateral movement of said carrying member; and teeth on said rockers, there being recesses in said base and carrying member to receive said teeth.

4. A device of the class described comprising a base; a central T-headed post on said base; eccentric rocker members on said base on opposite sides of said post; a coupler stem carrying member supported on said rockers, there being a T-slot in the under side of said carrying member to receive the head of said post, the retaining ledges of said slot sloping downwardly both ways from the center, adapted and arranged to prevent disengagement of said carrying member during normal operations of said carrying member but permitting disengagement and re-engagement upon extreme lateral movement of said carrying member; teeth on said rockers, there being recesses in said base and carrying member to receive said teeth; and a support for said base, adapted and arranged to prevent such disengaging lateral movement of said carrying member when the device is in operative position thereon.

5. A device of the class described comprising a support having a central opening for the passage of a coupler stem, the lower portion of said support being in the form of an open top channel; a base fitting into said channel, there being positioning lugs at the ends of said channel forcing said base into central position therein; a central T-headed post on said base; eccentric rocker members on said base on opposite sides of said post; a coupler stem carrying member supported on said rockers and having depending flanges embracing the upper portion of said post, there being a T-slot formed in the under side of said carrying member between said flanges to receive the head of said post, the retaining ledges of said slot sloping downwardly both ways from the center and adapted and arranged to prevent disengagement of said carrying member during normal operations thereof but permitting disengagement and re-engagement upon extreme lateral movement of said carrying member; means on said support adapted and arranged to prevent extreme lateral movement of said carrying member when the device is in operative position thereon; and teeth on said rockers, there being recesses in said base and carrying member to receive said teeth.

6. A device of the class described comprising a support having a central opening for the passage of a coupler stem, the lower portion of said support being in the form of an open top channel; a base fitting into said channel, there being positioning lugs at the ends of said channel forcing said base into central position therein; a central

T-headed post on said base; eccentric rocker members on said base on opposite sides of said post; a coupler stem carrying member supported on said rockers and having depending flanges embracing the upper portion of said post, there being a T-slot formed in the under side of said carrying member between said flanges to receive the head of said post, the retaining ledges of said slot sloping downwardly both ways from the center and adapted and arranged to prevent disengagement of said carrying member during normal operations thereof but permitting disengagement and re-engagement upon extreme lateral move-

ment of said carrying member; means on said support adapted and arranged to prevent extreme lateral movement of said carrying member when the device is in operative position thereon; and teeth on said rockers, there being recesses in said base and carrying member to receive said teeth, the recesses in said base extending entirely through the same and there being registering openings in the bottom of said channel to permit the escape of dirt.
